UNITED STATES PATENT OFFICE.

SUMNER E. BLACKSTONE, OF PITTSFIELD, NEW HAMPSHIRE.

COLLAPSIBLE WARDROBE.

No. 890,554.

Specification of Letters Patent.

Patented June 9, 1908.

Application filed October 9, 1907. Serial No. 396,556.

To all whom it may concern:

Be it known that I, SUMNER E. BLACKSTONE, a citizen of the United States, residing at Pittsfield, in the county of Merrimack 5 and State of New Hampshire, have invented an Improvement in Collapsible Wardrobes, of which the following description, in connection with the accompanying drawings, is a specification, like letters on the drawings representing like parts.

The object of my invention is to combine lightness, compactness, and completeness of service, and, to this end, I have provided exceedingly light sides, so arranged that they, 15 and also the top, can fold down flat against the back, and occupy only the space of their combined thicknesses, the sides being preferably skeleton in form, and provided with a folding shelf, specially constructed to receive 20 coat hooks, a folding garment rod, pockets for shoes, rubbers, etc., and a stand for umbrellas and canes.

The constructional details of my invention will be pointed out and further explained in 25 the course of the following description, reference being had to the accompanying drawings, in which

Figure 1 is a perspective view of the wardrobe complete, the front curtain being 30 broken away to show the internal construction; Figs. 2 and 5 are views thereof in side elevation, showing respectively the wardrobe open and closed; Figs. 3 and 4 are cross sectional views, showing respectively 35 the wardrobe closed and open.

The general construction of my invention will be best understood viewing Figs. 2-5, from which it will be seen that I preferably employ a solid back 1, to one vertical edge of 40 which is secured or integrally formed a projecting flange 2, having the same width as the opposite side 3, and to this flange is hinged at 4 a side 5, the side 3 being hinged at 6 to the opposite edge of the back 1. At 45 8 is pivoted on the back 1 a top 9, having side flanges 10 which embrace the upper ends of the two sides 3 and 5 when the wardrobe is open, as shown in Figs. 1 and 2, and embrace the entire upper part of sides and back when 50 the wardrobe is closed, as clearly shown in Figs. 3 and 5. The sides consist of a rectangular peripheral frame 11, over which is stretched cloth, leather, or tough paper 12, thereby providing a hollow or recessed inner 55 surface, having the frame as a flange or rim at its edges for holding and permitting the

proper pivoting, etc. of that portion of the device which is to be contained therein, and for which room has to be provided when the apparatus is folded. The contained portion 60 of the device preferably consists of a shelf 13, pivoted at 14 in the frame of the side 3, said shelf having a length permitting it to extend across between the frame edges of the opposite side 5, thereby serving to hold the wardrobe rigidly open when the shelf is raised as shown in Fig. 1, suitable suspending means for the swinging end of the shelf being provided, the same being herein shown as consisting of a hook 15 depending from the top of 70 the side 5. This shelf is arranged at the top of the wardrobe, preferably leaving a space sufficient simply for hats and the like, and it is purposely made of slats, not only for lightness, but to receive coat hooks for the suspension of garments from said rack. On the pivot rod 14 is suspended a hook 16 for receiving the free end of a rod 17, secured to a cross bar at its opposite end pivoted in the frame edges of the side 5, this rod 17 serving 80 the double purpose of coöperating with the shelf 13 in holding the wardrobe open, and also of receiving garments thrown over it or suspending garment hooks or the like. The frame of the side 3 is braced adjacent its 85 lower end with a transverse bar 19, from which is hung a series of folding shoe pockets 20, and above these I provide an umbrella ring 21 swiveled at 22 on a bracket 23 mounted to pivot vertically at 24 in a support 25 90 secured on the inner side of the frame of the side 3. The front of the wardrobe is preferably closed by a curtain 26, secured in any suitable manner, as by buttons or hooks 27.

In operation, when it is desired to use the 95 wardrobe, which we will suppose has been folded as shown in Figs. 3 and 5, the top 9 is first swung up on its pivot 8, and then the side 5 is swung outwardly until it strikes against the adjacent flange 10. This releases the 100 side 3, which is then swung outwardly in the opposite direction until it also strikes against the opposite flange 10. The shelf 13 is then swung up out of its nested position in the side 3 into engagement between the flanges 105 or frame edges of the side 5 and hooked in place, thereby holding the wardrobe absolutely rigid. Thereupon the rod 17 is swung upwardly from its nested position in the frame 5 into engagement with the frame 3, 110 where it is caught by the hook 16. This braces the wardrobe lower down than the

shelf 13, and gives still further rigidity. The ring 21 is then turned on its swivel 28 from its vertical closed position into its horizontal open position, and swung around as shown 5 in the drawings.

Having described my invention, what I claim as new, and desire to secure by Letters Patent is:

1. A wardrobe, comprising a back having 10 a forwardly projecting vertical flange at one edge, a side hinged at the opposite edge to swing inwardly flat against the front side of the back, an opposite side hinged to the front edge of said flange to swing inwardly flat 15 against the other side, said flange having a width permitting the first mentioned side to fold in behind the second mentioned side when the latter is folded in, a top pivoted at the upper end of the back to close down flat 20 over the back and the two sides when folded together, each of said two sides having an inwardly projecting frame at its edges, a shelf pivoted to and fitting snugly between the edges of the frame of one of the sides and 25 having a length to extend between and fit against the opposite edges of the frame of the opposite side when the wardrobe is fully opened, and means carried by the last mentioned side for detachably engaging the free 30 swinging end of the shelf to hold it in horizontal position.

2. A wardrobe, comprising a back having a forwardly projecting vertical flange at one edge, a side hinged at the opposite edge to 35 swing inwardly flat against the front side of the back, an opposite side hinged to the front edge of said flange to swing inwardly flat against the other side, said flange having a width permitting the first mentioned side to 40 fold in behind the second mentioned side when the latter is folded in, a top pivoted at the upper end of the back to close down flat over the back and the two sides when folded together, each of said two sides having an inwardly projecting frame at its edges, a shelf 45

pivoted between the edges of the frame of one of the sides and having a length to extend between the edges of the frame of the opposite side when the wardrobe is fully 50 opened, means carried by the last mentioned side for detachably engaging the free swinging end of the shelf to hold it in horizontal position, a bar mounted below said shelf in the frame of one side, a rod extending from said bar and arranged to swing against the 55 opposite side, and means for detachably holding said rod in its raised position.

3. A wardrobe, comprising a back having a forwardly projecting vertical flange at one edge, a side hinged at the opposite edge to 60 swing inwardly flat against the front side of the back, an opposite side hinged to the front edge of said flange to swing inwardly flat against the other side, said flange having a width permitting the first mentioned side to 65 fold in behind the second mentioned side when the latter is folded in, a top pivoted at the upper end of the back to close down flat over the back and the two sides when folded together, each of said two sides having an inwardly projecting frame at its edges, a shelf 70 pivoted between the edges of the frame of one of the sides and having a length to extend between the edges of the frame of the opposite side when the wardrobe is fully 75 opened, means carried by the last mentioned side for detachably engaging the free swinging end of the shelf to hold it in horizontal position, and an umbrella ring swiveled horizontally on a vertical pivoted bracket mounted on the inner side of the frame of one of 80 said sides.

In testimony whereof, I have signed my name to this specification, in the presence of two subscribing witnesses.

SUMNER E. BLACKSTONE.
